The ornamental design for a communication device, as shown and described.

DESCRIPTION

FIG. 1 is a front perspective view of a communication device showing our new design;

FIG. 2 is a rear perspective view thereof, with the lens rotated towards the rear surface;

FIG. 3 is a front view of FIG. 1;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines shown in FIGS. 1-8, that are immediately adjacent to the shaded areas, and define unshaded regions, represent the bounds of the claimed design and form no part of the claimed design, while all other broken lines depict portions of the communication device in which the design is embodied that form no part of the claimed design.
